UNITED STATES PATENT OFFICE.

ALBERT C. HINES, OF COLUMBUS, OHIO.

AUTOMOBILE THEFT-PREVENTION MEANS.

Application filed March 8, 1924. Serial No. 697,825.

To all whom it may concern:

Be it known that I, ALBERT C. HINES, a citizen of the United States, residing at Columbus, in the county of Franklin and 5 State of Ohio, have invented certain new and useful Improvements in Automobile Theft-Prevention Means, of which the following is a specification.

This invention relates to means for preventing the theft of automobiles, and particularly to means for preventing the flow of gasoline between the tank and the carburetor.

An object of the invention is to provide a 15 valve of suitable form, positioned in the gasoline feed pipe to the carburetor of the automobile, and mounted in a casing receiving said feed pipe, which casing entirely encloses the valve, and has connected portions 20 extended from the casing enclosing the valve to the instrument board of the vehicle, and connected with a suitable locking means having connection with the valve housed by said casing and its connection, whereby 25 when the valve is in the off position, said locking means will prevent unauthorized operation of the same, and the casing disclosing the operation means of the valve will prevent access to the connecting and operating connection between the valve and 30 the locking means.

The invention also includes other objects and improvements in the details of construction, and arrangement of parts, which 35 are more particularly pointed out in the following description and claim, directed to a preferred form of the invention, it being understood, however, that variations may be made in the specific construction and 40 arrangement of the parts, without departing from the scope of the invention as described and claimed.

In the drawing, forming a part of this application:

45 Figure 1 is a longitudinal sectional view, showing portions of the automobile, and the construction forming the present invention applied thereto.

Figure 2 is a view of the face of the combination lock used, for locking the valve controlling the feed of gasoline to the carburetor.

50 Figure 3 is a detail sectional view of the valve structure, which is connected in the gasoline feed pipe.

1 indicates the motor of the automobile,

having the usual intake manifold 2, and the carburetor 3 connected therewith, having the usual gasoline feed pipe 4, extending to the supply tank, which is not shown. 60 The motor 1, is covered by the usual hood 5, the dash board of the vehicle being indicated at 6, from the upper end of which extends the cowl 7, and at the rear end of which is the usual instrument board 8, positioned for the view of the driver, and for the operating handles of the several instruments mounted therein. A valve 9, is interposed in the gasoline feed pipe, at a position slightly in the rear of the dash 65 board 6, as clearly shown in Figure 1, and is of the usual fork type, having an operating rod 10, connected thereto, and extending upwardly to a position slightly below the cowl 7. A casing or housing 11 formed 70 of sections, is positioned around the valve 9 for completely housing the same, said casing having suitable openings for the gasoline feed pipe 4, and a tubular extension 12 adapted to receive and guide the 75 operating rod 10 of the valve stem, and also to receive a tubular casing member 13, adapted to completely cover and house the major portion of the operating rod 10 of 80 said valve stem, the upper end of said rod 85 being fitted on the tubular extension 14 of the removable head 15, of a casing 16, adapted to receive the upper end of the operating rod 10 for the valve, and provide a 90 bearing therefor, said operating rod being 90 provided with a suitable gear 17, meshing with another gear 18, within said casing 16. A shaft 19, is rotatably mounted in the casing 16, and extends through a tubular 95 housing 20, extending at an angle with respect to the tubular housing 13, and through the instrument board 8, being connected at its ends to the combination lock, indicated at 21, which is of any suitable form, adapted to be operated, upon a predetermined 100 combination, for either locking the valve 9, to close the passage of gasoline through the pipe 4, or for unlocking the same, to open said passage.

From this description, it will therefore, 105 be seen that the casing 16, may be mounted on the instrument board 6, and with which is connected the tubular casings 20 and 13, for housing the shaft 17, and the operating rod 10, in order to prevent access thereto, 110 when the same are positioned to hold the valve in closed position, so that a thief, or

other unauthorized person, is prevented from operating the valve, when locked by the combination lock member 21, for turning it to the open position.

6 It will be further noted, that it is substantially impossible to disassemble the parts housing the rods 10, and shaft 13, when the same are in locked position, as it is substantially necessary to remove the 10 combination lock 21 from connection with the tube 8, before the housing 16 can be removed from the tubular casing 13, and the dash board 6.

The invention, therefore, provides for a 15 simple construction, adapted to cut off and lock the gasoline supply to prevent operation of the engine by unauthorized persons, which may be readily operated from the instrument board of the vehicle in a simple 20 and convenient manner.

What is claimed is:

Means for preventing the unauthorized 25 use of automobiles comprising a valve adapted to be disposed in the fuel line, a housing completely enclosing said valve and having opposed openings through which

said feed pipe passes, said valve having a vertically extending operating stem, said housing being formed with a tubular extension providing a bearing for said stem, 30 a tubular casing secured on said extension and enclosing said operating stem, a gear casing mounted on the upper end of said tubular casing and provided with bearings, 35 said stem being rotatable in one of said bearings, a second tubular casing mounted on said gear casing and adapted to extend at one end through the instrument board of the vehicle, a lock mounted on the end of said last mentioned casing, a shaft rotatably mounted in said second named tubular casing and cooperating with said lock and having its inner end projecting into said gear casing, meshing gears carried by the inner end of said shaft and said stem, said 40 gears being housed in said gear casing, and all of said casings being separate and detachably connected with each other.

In testimony whereof I affix my signature.

ALBERT C. HINES.
